UNITED STATES PATENT OFFICE.

JOSEPH D. ANDERSON, OF ST. MARYS, OHIO.

ELECTRICAL GOVERNOR FOR GAS-ENGINES.

No. 889,086.

Specification of Letters Patent.

Patented May 26, 1908.

Application filed September 5, 1907. Serial No. 391,500.

To all whom it may concern:

Be it known that I, JOSEPH D. ANDERSON, a citizen of the United States of America, and resident of St. Marys, county of Auglaize, 5 State of Ohio, have invented certain new and useful Improvements in Electrical Governors for Gas-Engines, of which the following is a full and clear description, reference being had to the accompanying drawing, in which—

10 Figure 1 is a vertical sectional view of my improved governor, and Fig. 2 an end view thereof.

This invention has relation to that class of governors for internal combustion engines in 15 which means are embodied for breaking the ignition circuit upon the attainment of an abnormal speed and thus prevent the charge being ignited, and it is especially designed for use in connection with an engine provided 20 with means for retaining in the cylinder each charge until it is exploded, thus accomplishing a material saving in fuel and avoiding the danger and nuisance of ejecting unburned charges into the atmosphere, as more fully 25 hereinafter set forth.

Referring to the drawing annexed by reference characters, *a* designates the main shaft of the engine and *b* a portion of the hub of the fly-wheel affixed thereto. Mounted on 30 the shaft adjacent to the hub is a sleeve *c* which is adapted to be rotatably adjusted on said sleeve to advance or retard the sparking, any suitable means being employed for rotating the sleeve and locking it in its adjusted 35 position. I prefer using for this purpose a rod *d* pivotally connected to a lug depending from the sleeve and having at its other end a slot by means of which and a suitable nut and bolt the rod may be locked at any point of 40 adjustment to a suitable part of the engine frame. Bolted insulatedly upon the upper side of this sleeve is a plate *e* which at its inner edge is provided with an upturned flange *f* whose upper edge is curved concentrically with the shaft of the engine and is 45 adapted to afford a contacting surface for the rotating element of the device.

Bolted by means of a bolt *g* and a nut *h* to the adjacent edge of the hub is a metal 50 bracket *i*, suitable insulation *j* being provided to insulate this bracket from the hub. Projecting from this bracket outwardly over the contact flange *f* is an arm *k* in which is 55 adjustably mounted a radial tube *l* which incloses a contact ball *m*, a spiral spring *n*,

and a screw plug *o*. A spring presses the ball toward the inner end of the tube and the plug enables the tension of this spring to be adjusted. The bore of the tube is slightly narrowed at its inner extremity so as to permit the ball to protrude a short distance beyond the inner end of the tube. 60

The bolt *g* is extended radially a considerable distance to form a guide rod *p* for a governor weight *q*, and this governor weight is 65 normally pressed inwardly by a coiled spring *r* whose tension may be regulated by a nut *s*. This weight is normally pressed against an integral arm *t* of the bracket *i* through a hole in which arm the guide rod extends without 70 touching the arm.

The conductor of the ignition circuit is connected to plate *e* by a suitable binding post, such as *u*, so that when the contact ball *m* rolls over the contacting face of the flange *f* 75 the current will pass through the ball, the sleeve, the bracket *i* and its arm *t*, and thence through the metal weight *q* down through the guide rod and bolt to the engine frame. It will thus be observed that by manipulating 80 rod *d* the sparking may be regularly advanced or retarded without stopping the engine. It will be observed also that upon the attainment of an abnormal speed the governor weight will ride outwardly on the guide rod 85 and thus break contact between it and the insulated bracket *i* and thus prevent the sparkers from igniting the charge.

Having thus fully described my invention, what I claim as new and desire to secure by 90 Letters Patent, is—

1. In an internal combustion engine, the combination of a sleeve rotatably mounted on the shaft of the engine, means for rotatably adjusting and locking this sleeve, an 95 insulated contact member mounted on this sleeve and having a curved contact face, and automatic circuit-breaking means mounted on the adjacent hub of the fly-wheel and comprising a bracket and means for bolting 100 it insulatedly to the hub, this bracket being provided with an arm, a tube mounted on this arm and adapted to be radially adjusted, a ball contact piece protruding from the inner end of the tube, a spring and an adjustable plug for bearing on said ball contact, and a governor weight normally in circuit with said bracket and sleeve. 105

2. The combination with an internal combustion engine, of one contact member 110

mounted rotatably on the shaft of the engine adjacent to the fly-wheel, a metallic bracket and a bolt for fastening it to the periphery of the hub of the fly-wheel, said bolt being 5 extended radially outward and carrying a governor weight and an adjustable spring, the spring serving to normally press the governor weight inwardly against a part of the bracket, whereby the governor weight forms 10 a part of the circuit, and a contact member

carried by said bracket, substantially as set forth.

In testimony whereof I hereunto affix my signature in the presence of two witnesses this 28 day of August 1907.

JOSEPH D. ANDERSON.
